UNITED STATES PATENT OFFICE.

GEORGE B. GEISER, OF PHILADELPHIA, PENNSYLVANIA, ASSIGNOR TO BERGER BROS. COMPANY, A CORPORATION OF PENNSYLVANIA.

SUPPORT FOR GUTTER-HANGER CIRCLES.

Application filed January 27, 1925. Serial No. 5,030.

My invention relates to means for securing gutter hanger circles to buildings.

Heretofore various devices have been provided for supporting gutter hanger circles on buildings, the circles in turn acting to support gutters.

Such devices consist ordinarily of a plate for attachment to a roof or under the eaves of a roof and a stem to which the circle is adapted to be adjustably secured, the plate and stem being secured together.

In many such structures heretofore produced, certain disadvantages have been present, especially in that the plate and stem are insufficiently secured together, or when firmly secured the securing means interferes with adjustment of the circle in relation to the stem.

Now it is the object of my invention to provide means for supporting circles of such design and construction that a support of a high degree of efficiency will be provided and at the same time one which will permit of full adjustment of the circle.

Further objects of my invention are to produce a support which will be so constructed as to promote economy of material and workmanship in its manufacture and at the same time of a superior degree of efficiency and durability in use.

Having now indicated in a general way the nature and purpose of my invention, I will proceed to a detailed description thereof with reference to the accompanying drawings in which is illustrated a preferred embodiment and in which:

Figure 1 is a side elevation of the support embodying the invention with a circle secured thereto.

Figure 2 is a front elevation of a support.

Figure 3 is a plan view of the support shown in Figures 1 and 2.

In the several figures *a* indicates a stem, made of suitable material and of channel section. The stem is provided with a series of spaced bolt holes *b* adapted for the passage of a bolt *c* which passing through one of a series of bolt holes *h* in the heel of the circle *i* aligned with one of the holes *b*, serves to secure the circle to the stem.

The heel of the circle is provided with a

ridge, through which the holes *h* pass, adapted to enter the channel of the stem and prevent turning of the circle about the bolt. The holes in the stem and circle are differently spaced enabling the circles to be secured at various heights on the stem by aligning various holes, all as is well known.

d indicates a plate, provided adjacent its ends with holes *e* for the passage of means for securing the plate to a building.

The plate *d* is made longer than its finished length and is folded to form a vertical fold or flange *f*, as shown in Figures 2 and 3. The plate is so folded that the flange *f* will lie to one side of the center of the plate.

The plate *d* is positioned against a side of the stem *a* at one end of the stem and secured to the stem by a rivet *g* passed through the flange *f* and the back of the stem *a*, with one of its flanges lying along the outer face of plate *d* as shown in Figures 2 and 3.

When the plate and stem are secured together the stem will be positioned midway between the ends of the plate, as shown in Figure 2.

It will now be apparent that the plate *d* may be readily attached to a building and that a circle may be readily attached to the stem *a* and may be adjusted in the channel of the stem without interference.

It will be noted that the provision of the fold or flange *f* adapted to be secured to the back of the stem provides a highly efficient securing means, readily produced and one which will not work loose or break, at the same time the fold or flange does not obstruct the channel, in the stem, in which the circle is adjusted.

Having now fully described my invention, what I claim and desire to protect by Letters Patent is:

A support for a gutter hanger, comprising a plate having a base, a two ply flange extending laterally therefrom between its ends, there being securing openings through the base at each side of the flange, for the reception of fastening means for securing the base of the plate against a supporting surface, said flange being formed by doubling the intermediate portions of the plate,

and a gutter circle supporting stem of channel cross section secured with the back of its web against a side face of the flange by securing means passing through the web of the stem and the two plies of the flange, whereby the two plies of the flange and the

of the stem extending along the base, whereby the stem is held against movement about the securing means.

10

In testimony of which invention, I have hereunto set my hand, at Philadelphia, Penna., on this 26th day of January, 1925.

GEORGE B. GEISER.
